G. KOLLSTEDE

CUFF BUTTON

Filed April 20. 1923

Twelve hours.

George Kollstede

By Horatio E. Bellows
Atty.

UNITED STATES PATENT OFFICE.

GEORGE KOLLSTED, OF PROVIDENCE, RHODE ISLAND, ASSIGNOR TO V. E. BLACK COMPANY, INCORPORATED, A CORPORATION OF RHODE ISLAND.

CUFF BUTTON.

Application filed April 20, 1923. Serial No. 633,434.

To all whom it may concern:

Be it known that I, GEORGE KOLLSTED, a citizen of the United States, residing at Providence, in the county of Providence and 5 State of Rhode Island, have invented certain new and useful Improvements in Cuff Buttons, of which the following is a specification.

My invention relates to cuff buttons of the 10 separable type and more particularly to those whose locking or clamping members are released by manually operating a member projecting from the button proper.

Heretofore the operating member was a 15 post slidably mounted in and projecting from the center of the head whereby ornamentation of the face of the button head was prevented.

The essential objects of my invention are 20 to overcome the above disadvantage; to prevent rotation of the button in the button hole; to prevent rotary movement of one button member relatively to the other whereby it is possible to employ button heads of oblong design; and to attain these 25 ends in a simple and inexpensive structure.

To the above ends essentially my invention consists in such parts and in such combinations of parts as fall within the scope 30 of the appended claims.

In the accompanying drawings which form a part of this specification,

Figure 1 is a side elevation partially in 35 central vertical section of my button with the parts engaged,

Figure 2, a like showing of the same with the parts released,

Figure 3, a section on line 3—3 of Figure 1,

Figure 4, a bottom plan view of one of the 40 separable socket members,

Figure 5, a section on line 5—5 of Figure 1, and

Figures 6, 7, and 8, detail views of the 45 link member, the operating member, and the spring respectively.

Like reference characters indicate like parts throughout the views.

My button comprises two socket or separable members 10 and 11 alike in every detail, so that a description of one will suffice for both. Each of these members comprises a head 13 consisting of an oblong plate 14 engaged by a peripheral rolled over portion 50 or flange 15 to the top of a tubular tapering

post 17 of rectangular cross section. The opening or socket 18 formed in the retracted portion of the post is therefore rectangular and oblong in shape. Upon the narrow end of the post is a lateral circular flange or shoe 60 20 having a central flaring portion 21 and a peripheral bead 22. The upper portion of the post has a longitudinal slot 24 adjacent the plate 14.

In each socket member is an operating 65 member comprising an oblong body or plate 26 integral with whose end is a laterally projecting downwardly inclined finger 27 provided with a terminating knob 29. The finger passes through the slot 24. Midway 70 its length the plate 26 has lateral, resilient, inwardly converging fingers 31 preferably curved to conform to the inclined curvature of the post 17 with which it is adapted to contact. The plate 26 is preferably somewhat 75 resilient and one end portion 33 rests upon the upper portion of the post 17 and in contact with the plate 14 where it is fulcrumed or held, with the finger 27 normally resting in the bottom of the slot 24. 80

A flat arched spring 34 whose ends rest on top of the post has an intermediate portion engaging the upper face of the plate 26.

A link member 36 comprises a shank portion 37 rectangular or oblong in cross section, and ends heads 38 and connecting necks 39; both heads and necks being of oblong 85 cross section.

The operation of my button is as follows. 90 One of the socket members, say 10, has one of the heads 38 of the link member pressed upwardly into the socket opening 18 contacting with and elevating the fingers 31 against the pressure of the spring 34 until space permits the spring to depress the fingers, enter the neck 39 and embrace the swells of the head 38. The head is now locked by the fingers which are clamped by the head against the post wall 17. The head can now be released only by manually upwardly tilting, through the finger 27, the plate 26, and thereby elevating the fingers 31 to a plane adjacent the maximum breadth of the head, and the head is then withdrawable. The socket member 11 may next be similarly 105 engaged with the second head.

It will be noted that the rectangular or flattened shape of the posts 17 makes the button nonrotatable in the button hole; also that the transversely elongated shape of the 110

heads 38 and necks 39 of the link member cooperate with the elongated sockets 18 to prevent any rotation of the members relatively to the link member and to each other.

5 It will be further observed that the surfaces of the end plates 14 of the socket members are unbroken and therefore free for any desired ornamentation.

I claim:—

10 1. In a cuff button, a socket member comprising a tubular inwardly converging post provided with a longitudinal slot, a head upon the outer end of the post, and a flange upon the inner end of the post, a resilient 15 tilttable plate supported at one end by the post, a finger upon the other end of the plate extending through the slot, locking fingers on the plate engageable with the retracted portion of the post, a spring in the head engaging the plate, a link, and a head on the link adapted to enter the retracted end of the post to receive the locking fingers.

2. In a cuff button, a socket member comprising a tapering tubular post provided at 25 its inner end with a transversely oblong socket and in its outer margin with a longitudinal slot, a head upon the outer end of

the post, and a flange upon the inner end of the post, a resilient tilttable plate attached at one end to the post, a finger on the other end of the plate extending through the slot, locking fingers on the plate engageable with the socket portion of the post, a spring in the head engaging the plate, a link, and a transversely elongated head upon the link 30 35 adapted to register in the socket and receive the locking fingers.

3. In a cuff button, two socket members comprising tapering transversely oblong rectangular posts provided with lateral slots and forming with their open inner ends oblong sockets, heads on the outer ends of the posts, flanges on the inner ends of the posts, a link comprising a body and transversely oblong heads upon the body adapted to enter the sockets, vibratory plates in the posts, operating members on the plates, locking fingers on the plates engageable with the link heads, and springs in the first mentioned heads engaging the plates.

In testimony whereof I have affixed my signature.

GEORGE KOLLSTED.
